CLAIM

The ornamental design for a combined bell handle and clapper chain, as shown and described.

DESCRIPTION

FIG. 1 is a front elevational view of a combined bell handle and clapper chain embodying my new design, the rear being substantially identical and the bell housing and clapper being shown in broken lines for illustrative purposes only;

FIG. 2 is a side elevational view thereof; and

FIG. 3 is a top plan view thereof.

FIG. 1

FIG. 3
